UNITED STATES PATENT OFFICE.

ELEANOR V. SHEPPARD, OF CHICAGO, ILLINOIS.

SINK SPLASH GUARD.

Application filed February 17, 1928. Serial No. 254,982.

My invention in general relates to devices for preventing the spilling and splashing of water from sinks and the like.

More particularly my invention relates to 5 a novel anti-splash guard adapted for instant attachment to and detachment from a sink.

Another object of my invention is to provide a device of this kind of simple and in- 10 expensive construction particularly adapted for quantity production.

A further object of my invention is to provide a splash guard adapted to be instantly applied to all types of sinks, wash stands, tubs 15 or similar plumbing fixtures.

Other objects and advantages of the method and construction herein employed will appear more fully in the hereinafter specification, when taken in connection with 20 the accompanying drawings, in which:

Fig. 1 is a perspective view of my device.

Fig. 2 is a front elevational view of my device operatively attached to a conventional sink.

25 Fig. 3 is a cross section taken on line 3—3 of Fig. 2.

With more particular reference to the drawings wherein similar characters of reference indicate corresponding parts in the 30 several views, A designates my splash guard consisting preferably of an oblong sheet of metal 11 which is suitably enameled or provided with a coating of porcelain. At the 35 top of the metal sheet 11, I form a curve or roll 12 the end edges of which are slightly in-turned for a purpose hereinafter described. The lower portion of the metal sheet has a crimp or folded portion 13 which serves to 40 re-inforce the entire sheet.

45 Secured to the body of the metal sheet 11 by rivets 11' or other suitable means, are resilient brackets B—B' which are made of strips of metal 14 within rubber tubing 15, and bent to form an involute portion 16 with a beading or roll 17 at the end thereof.

The mode of operation of my invention has been in large measure indicated by the foregoing description in connection with the several accompanying views, but will be more 50 fully apparent from the following brief explanation:

When use is made of the conventional sink, much annoyance has been caused by the splashing of water from the faucets. To 55 prevent this it is desirable to have some means preferably susceptible of instant attachment

and which may be as quickly removed when the sink is not being used. I attain this desirable object by the embodiment shown in the drawings. In the type of sink shown in 60 Fig. 3, it will be observed that by reason of the roll or involute beading at the top of the sink, a special form of clamping member will be essential to apply a splash guard securely thereto. As a particular feature of my invention I provide novel resilient bracket members B—B', the involute portion of which is adapted to permit the inwardly curving edge of the roll of the sink to enter 65 into and to register with the convolution of 70 my novel brackets B—B'. My bracket is applied to the form of the sink shown in Fig. 3 in an inverted position, the extremity 18 of the roll of the sink being the pivot point about which the brackets B—B' partly revolve and swing into the position as shown. To remove the splash guard it is merely necessary to draw the body of the guard backward 75 in a clockwise direction as viewed from the disclosure in Fig. 3, thus permitting the instant disengagement of the device. 80

The inturned edges of the roll 12 serve to prevent a premature spilling of the accumulated drops of water which may run together when my splash guard is being detached, the 85 edges providing a scoop formation for the water when the guard is inverted, preparatory to tipping and draining.

It is evident that my invention is susceptible to some variation and modification; hence 90 I do not confine myself literally to the details as set forth but wish to take advantage of such changes and embodiments as fairly fall within the scope of the appended claims.

What I claim as new and desire to secure 95 by Letters Patent is:

1. A device of the kind described comprising a sheet of metal having a flared roll at its top portion and serving as a sink splash guard, a plurality of resilient brackets secured to said sheet of metal, each of said brackets having a beading with a reentrant portion formed with an integral involute formation registering with an involute portion on the rolled edge of a cooperating sink 100 whereby said splash guard may be applied to and supported by the sink, by means of said brackets. 105

2. A sink splash guard comprising a plurality of resilient rubber covered brackets secured to an oblong sheet of metal serving as a main body of the guard, said sheet of metal 110

being crimped at its lower end and having a flared portion at its upper part, each of said brackets having an integral involute curve terminating in a resilient beading whereby said brackets may be applied to a corresponding involute portion of the sink and then partially revolved around said curved upper por-

tion of the sink in a manner to secure engagement with and a ready detachment from the sink.

10

In testimony whereof, I have signed my name to this specification.

ELEANOR V. SHEPPARD.
